UNITED STATES PATENT OFFICE.

GEORGE R. DE NISE, OF DENVER, COLORADO.

PHYSICAL-CULTURE APPARATUS.

No. 902,946.

Specification of Letters Patent.

Patented Nov. 3, 1908.

Application filed June 8, 1907. Serial No. 378,011.

To all whom it may concern:

Be it known that I, GEORGE R. DE NISE, a citizen of the United States of America, residing at Denver, in the county of Denver and State of Colorado, have invented certain new and useful Improvements in Physical-Culture Apparatus, of which the following is a specification.

This invention relates to physical culture apparatus of the type intended to produce a stretching action upon the human body for the purpose of strengthening the nervous system and incidentally increasing the height of the user by restoring the natural elasticity to the abnormally hardened cartilaginous tissue and exercising the many muscles which by want of continual action, are weak or undeveloped.

The objects of the invention are to produce an apparatus of the class named in which the maximum of simplicity and economy of construction shall be combined with durability, practicability in use and efficiency of action and which, while adapted for the use of all persons irrespective of their physical proportions, may be reduced in compass so as to be suitable for shipping or storing purposes.

I attain these objects by the mechanism illustrated in the accompanying drawings, in the various views of which like parts are similarly designated and in which

Figure 1—represents a plan view of the apparatus, Fig. 2—a side elevation thereof, Fig. 3—an enlarged, fragmentary plan view of the head-end of the device, Fig. 4—a similar view of the foot end, Fig. 5—a view illustrating the head and upper parts of the body of a person equipped with the combined head and chest gear employed in the practice of my invention, Fig. 6—a perspective interior view of the cap or head gear employed in my device, Fig. 7—a top view of the said cap, Fig. 8—an enlarged transverse section taken along line 8—8, Fig. 1, Fig. 9—an enlarged cross section taken along line 9—9, Fig. 1, Figs. 10 and 11,—fragmentary plan views of the foot end of the device showing modified manners of arranging the tackle employed to communicate the force exerted upon the operating parts of the machine, to the human body, Fig. 12—a fragmentary side view of the body part of the apparatus illustrating the arrangement of the operating mechanism, Fig. 13—a view of a human head equipped with the cap or head

gear illustrated in Figs. 6 and 7, and Fig. 14—a view of a human foot illustrating the manner of applying the foot straps by which the lower extremities of the body are attached to the stretching appliances.

Referring to the drawings, my apparatus consists of a table or bench 2 comprising the, in practice, horizontal deck 3 provided with preferably integral, depending sides or flanges 4 and supported upon legs 5, the lower extremities of which are bent to provide feet 5^a.

The legs 5 at each end of the table are connected at their upper ends by integral cross bars 6 and are pivotally secured intermediate the flanges 4 by means of bolts or rivets 7. When the device is not in use these connected legs may be folded inside the sides of the table as shown in Fig. 2 of the drawings, and when the apparatus is in operative condition, they are turned at right angles to the deck 3 and secured in this position by means of detachable pins 8 inserted through registering apertures in the upper parts of the legs and the adjacent sides of the table.

Rotatably secured in straps 9 upon the flanged upper end of the table 2, are the stops 10 designed to relieve by engagement with the axillæ of the patient, the head, neck and contiguous parts of the greater part of the tension produced by the stretching action upon the feet and which comprise individually the spindle 10^a, the therewith parallel engaging portion 10^c and the interposed shank 10^d.

To prevent injury to the parts of the body with which the stops 10 are in contact during the operation of the apparatus, the engaging parts 10^a may be provided with sleeves 11 composed of rubber, felt or other elastic substance as shown in Fig. 3 of the drawings.

Extending outwardly from the head end of the table is a yoke 12 the angularly arranged, normally vertical extremities 12^a of which are disposed upon the outer surface of the flanges 4 and are pivotally secured thereto by means of the before named bolts or rivets 7 which provide the fulcrum for the adjacent legs 5.

The yoke is held in its extended position by means of the before mentioned pins 8 which project through correspondingly arranged apertures in the arms 12^a and when not in use may be folded upon the upper or lower surface of the table.

A continuous belt 13 made of canvas, rub-

ber or other flexible material is stretched between the parallel side-bars 12^c of the yoke 12 to afford a comfortable support for the head of the patient, who during the operation of the apparatus, reclines upon the deck 3.

An opening 14 in the head-support 13, is intended to admit the nose and mouth of the patient, should he desire to undergo the stretching operation while lying face down-10 ward.

The cross-bar 12^d of the yoke is provided with a centrally applied buckle 15 to which the hereinafter to be described headgear may be attached, and near its ends, with hooks 16 15 which afford means to secure straps placed around the wrists of the patient, when, to promote the development of the thoracic muscles and organs, the body is subjected to the stretching action with the arms extended 20 above the head.

As the means by which the arms are attached to the hooks 16, form no part of the device, their illustration has been omitted from the drawings.

25 Hingedly secured upon the opposite or foot-end of the table 2 is an extension or foot board 17, formed with integral, depending flanges 18 and, in practice, supported at its outermost end upon legs 19 connected by an 30 integral cross bar 20 and pivotally secured intermediate the flanges, by means of a bolt or threaded rod 21.

Pins 22, projecting through registering apertures in the legs and adjacent flanges, secure the former when turned at right angles to the plate 17, while a bolt, sliding catch or other suitable fastening device 17^a is applied below the juxtaposed ends of the foot-board and the body portion of the apparatus to 40 firmly secure them in the extended or opened position.

The extension 17 of the device serves in practice, as a support for the feet and contiguous parts of the legs of the patient, when 45 reclining upon the deck 3, and as a means for securing the tackle or combination of ropes and two or more blocks compounded to exert increased force upon the body under treatment.

50 In my preferred form, illustrated in Figs. 1, 2 and 4, the tackle consists of a standing, double block 23 which may be secured upon the board, or, as is shown in the illustration, may be connected to a suitable indicatory 55 appliance 24 through instrumentality of which the force exerted upon the body may be determined.

The indicator, as shown in Fig. 8 of the drawings, consists of a dial 25 erected in perpendicular position upon the extreme end of the board 17 and upon which is fulcrumed a hand or lever 26, the long arm of which is arranged to denote the amount of exerted force upon a graduated scale 27, while its shorter

arm connects with the eye 23^a of the block 23 65 by means of a rope 28 rove around a fixed sheave 29 which changes the direction of its motion.

The lower extremity of the long arm of the lever 26 is connected with a fixed point on the dial by a coiled spring 30, the elasticity of which in coöperation with the mechanical advantage gained through the inequality in the length of the arms, measure the amount of force exerted through instrumentality of 75 the tackle and the therewith connected operating mechanism.

The scale upon the dial is preferably arranged in accordance with the age and physical condition of the various persons by whom 80 the apparatus may be used, as illustrated in Fig. 8, in which the graduations are arranged at a distance equaling twenty five pounds of pressure.

To prevent possible injury to the patient 85 by excessive stretching, the graduations on the dial denote in addition to the amount of force exerted by manipulation of the operating mechanism the maximum amount of pull that persons of various ages and of either sex 90 can withstand without harming the parts of the body most affected by the stretching process. For example, a force of twenty five pounds exerted upon the body, is indicated by the fourth graduation and is the maximum pressure for children of from five to ten years of age; one hundred and twenty five pounds for children of from ten to fourteen years; one hundred and fifty pounds for youths, female adults and aged persons; and 100 two hundred pounds the maximum for male adults.

The double block 23 being thus anchored, a rope 31 normally secured at one of its extremities to a cleat 32 upon a side of the main 105 body 2 of the device, is passed around one of its sheaves, thence around the sheave of a running block 33, from where it extends around the second sheave of the standing block, to a winch 34 to which it is secured. 110

The latter comprises a shaft 35 rotatably mounted in the sides 4, transversely of the table 2, and provided with an enlarged extension or drum 36 to which the fall of the rope 31 is fastened and which carries upon its outer 115 extremity a crank 37, by manipulation of which the mechanism is actuated.

A gravity dog 38 pivotally secured to the side of the table 3, engages the teeth of a ratchet wheel 39 fixed upon the drum 36 in 120 juxtaposition to the said side for the purpose of preventing retrograde motion of the shaft while the pressure is being applied.

The standing part of the rope, between the block 23 and the cleat 32 is, as shown in Fig. 125 2 of the drawings, rove through two pulleys 40 and 41, fixed upon the adjacent portion of the side 4 and whose function is to prevent,

by frictional engagement, slackening of the rope when for adjustment purposes, the latter is detached from the cleat.

The reference numeral 42 designates the gear by which the feet of the person reclining upon the device, may be connected with the tackle and which comprises two members 43 each composed of an ankle strap 44 which, in practice, is fastened around the tarsus of the patient by the use of a buckle 45, and a flexible loop 46, the ends of which are secured to the strap 44 and which, when the gear is in operative position, passes around the sole of the user's foot.

15 The loops of the two members 43 of the gear are connected by a strap 47 which passes loosely through the eye 33^a of the running block 33 of the tackle.

The tackle illustrated in Fig. 10, may be substituted for that hereinbefore described, for the purpose of exerting an increased amount of force upon the body of the patient without increase of power applied to the winch. In this construction, three standing blocks 25 48, 49 and 50 are equidistantly secured upon the outer extremity of the foot plate 17 in transverse alinement and the rope 53, the end of the standing part of which is secured to the cleat 32, passes around the first sheave 48, 30 through a running block 51 from where it passes around the center pulley 49, to a second running block 52 to be rove through the last sheave 50 and secured to the winch. The connecting strap 47 of the foot gear, is in this 35 case omitted and the members 43 secured respectively to the two running blocks 51 and 52.

A second modified manner of compounding the sheaves is illustrated in Fig. 11 of the drawings and comprises two standing blocks 40 54 and 55 secured in transverse alinement at equal distances from the center of the foot support 17 and the rope 56 which passes from its fastening point around the first sheave 54, thence around a running block 57, 45 and through the block 55 to the winch. The foot gear 42 may in this case, be connected with the tackle in a manner identical to that shown in Fig. 4, or the strap 47 may be rove through a block 58 which is secured to the 50 running block 57, for the purpose of reducing friction.

The head gear 59, illustrated in Figs. 6, 7 and 13, is employed to secure the patient's head in a fixed relation to the upper or head 55 portion of the table and is, by reason of the frailty of the parts to which it is applied, a factor of my device the construction of which involves the utmost care and precision. It consists of a cap 60 composed of leather, canvas, cloth or other flexible material and preferably internally cushioned so as to prevent injury to the skin of the wearer. The rear-most portion 60^a of the cap is extended so as to cover the posterior base of the skull and

the foremost part is split as at 60^b to permit 65 adjustment in accordance with different sizes of heads. A strap 61 having a buckle 62, surrounds the cap near its lower edge and may be held in place in transverse loops 63. This strap is so arranged that when the cap 70 is placed upon the patient's head, its fore part passes around the forehead while its rear-most portion presses upon the occiput or posterior part of the calvarium. The cap 60 is furthermore provided with two straps 64 75 and 65 the ends of each of which are secured upon opposite points thereof and which, crossing each other, are connected by a ring 66.

The straps are so placed upon the cap that when the latter is placed upon the head of 80 the reclining patient, the point at which they cross is in alinement with the spinal column, thereby assuring the pressure exerted upon the body to be applied directly to the cartilage intermediate the vertebrae. 85

A strap 67 secured to the ring 66 is designed to fasten the head gear to the buckle 15 upon the yoke 12. To relieve the head of part of the pressure exerted thereon during the operation of the apparatus, use may be 90 made of the appliance illustrated in Fig. 5, consisting of a belt 68 which in practice, is secured around the chest of the patient below the arm pits and which is adjustably connected with the band 61 of the head gear by 95 interposed straps 69.

To ascertain the number of inches or fractions thereof, to which the body is extended during the operation, a graduated scale 70 is applied to the foot support 17, upon which 100 the position of the patient's feet may be indicated before and after the stretching process.

Having thus described the mechanical construction of the device, its operation will be readily understood. The apparatus may 105 be operated by the patient himself or by an assistant. After the head dress is adjusted upon the head of the person under treatment, in the manner hereinbefore described, he places himself upon the deck 3 in a sitting 110 posture and having loosened the end of the rope 31 from the cleat 32, secures the elements 43 of the foot gear to his feet in the manner illustrated in Fig. 14. He now assumes a reclining position, the head in engagement with the resilient support 13, after which the strap 67 is fastened to the buckle 15 of the yoke 12. Having pulled the standing part of the rope until its running and fall portions are taut, he re-fastens the end thereof 120 to the cleat 32 and having adjusted the stops 10 in engagement with the armpits, he manipulates the crank 37 of the winch until the desired degree of tension is attained as indicated upon the dial 25. To release the tension, the end of the rope is unfastened from the cleat 32, or the gravity dog lifted out of engagement with the ratchet wheel. In case

the patient undergoes the treatment to cure certain thoracic organic or muscular derangements, he elevates the arms above the head after which the wrists are connected by means 5 of the aforesigned straps, to the hooks 16 on the yoke 12. In this case the use of the stops 10, as well as the head gear may be discarded.

Having thus described my invention, what 10 I claim is:—

1. A physical culture apparatus comprising a body support adapted to sustain a body in a reclining position, means to fix the upper part of the body thereon, a gear adapted to engage the lower limbs of the body and block and tackle appliance arranged upon the said support to impart a stretching action to the said gear by manipulation of either of the ends of the rope included therein.
2. A physical culture apparatus comprising a body support, means for holding the upper part of the body in position thereon, a gear adapted to engage the lower limbs of the body, a block and tackle appliance connected with the said gear, means to adjustably secure the normally standing extremity of the rope included therein, and mechanical means adapted to apply power to its opposite end or fall.
3. A physical culture apparatus comprising a body support, means to fix the upper part of the body thereon, a gear adapted to engage the lower limbs of the body, and a tackle and block appliance including a standing block upon the support, a running block connected with the gear and a rope in operative relation to the blocks one of its ends being adjustably held at a stationary point, and mechanical actuating means connected with its opposite end or fall.
4. A physical culture apparatus comprising a support adapted to sustain a body in a reclining position, means upon the said support to fix the upper part of the body thereon, a block and tackle appliance upon the said support and two members respectively adapted to be attached to the lower limbs of the body and self-adjustably connected with the running part of the said appliance.
5. A physical culture apparatus comprising a support adapted to sustain a body in a reclining position, means thereon for holding the upper part of the body, a gear including two members adapted to be attached to the lower limbs of the body, a block and tackle appliance upon the support including standing and running blocks and a flexible connection between the said members self-adjustably connected with the latter and mechanical means adapted to actuate the said appliance.
6. A physical culture apparatus comprising a support adapted to sustain a body in a

reclining position, means to fix the upper part of the body thereon, a block and tackle appliance upon the said support and including running and standing blocks, mechanical means to actuate the said appliance, a gear connected with the appliance and adapted to engage the lower limbs of the body and indicatory means connected with the standing block and arranged to indicate the amount of force exerted upon the said gear through instrumentality of the said appliance.

7. A physical culture apparatus comprising in combination with a support adapted to sustain a body in a reclining position, a graduated member fixed thereon, a lever fulcrumed upon the said member, a block and tackle appliance connected with an arm of the said lever, a resistance device attached to its opposite arm, a gear adapted to engage the lower extremities of the body and connected with the said appliance and means upon the support to fix the upper part of the body thereon.

8. A physical culture apparatus comprising a support adapted to sustain a body in a reclining position and including two hingedly connected members, means upon one of the said members to fix the upper part of the said body thereon, and stretching means secured upon the opposite member, adapted to be attached to the lower limbs of the body.

9. A physical culture apparatus comprising a body support, stretching means at one of its ends adapted to connect with the lower limbs of a patient reclining thereon, and a head gear attached to the opposite end of the said support and including a cap, a strap surrounding its lower portion and arranged to simultaneously engage the brow and the occiput of the patient's head and two intersecting straps upon the cap, their point of intersection being substantially in alignment with the spinal column when the cap is adjusted upon the patient's head in the aforesaid manner.

10. A physical culture apparatus comprising a body support, stretching means at one of its ends adapted to connect with the lower limbs of the patient reclining thereon, a head gear attached to the opposite end of the support and including a cap and a strap surrounding its lower portion and arranged to simultaneously engage the brow and occiput of the patient's head, and a belt arranged to embrace the patient's thorax, adjustably connected with the said strap.

In testimony whereof I have affixed my signature in presence of two witnesses.

GEORGE R. DE NISE.
